UNITED STATES PATENT OFFICE.

RICHARD KUENSTLER, OF CHICAGO, ILLINOIS.

PHONOGRAPH-STOP.

1,310,484.

Specification of Letters Patent. Patented July 22, 1919.

Application filed December 9, 1918. Serial No. 265,894.

To all whom it may concern:

Be it known that I, RICHARD KUENSTLER, a citizen of the United States, and a resident of the city of Chicago, county of Cook, 5 and State of Illinois, have invented certain new and useful Improvements in Phonograph-Stops, of which the following is a specification.

My invention relates to improvements in 10 phonograph stops, and has for its object the production of mechanism of this character which will be of durable and economical construction, and through the medium of which a phonograph will be automatically 15 stopped upon opening of the cabinet cover.

Other objects will appear hereinafter.

The invention consists in the combinations and arrangements of parts hereinafter described and claimed.

20 The invention will be best understood by reference to the accompanying drawings forming a part of this specification, and in which,

Figure 1, is a top plan view of a phonograph embodying the invention, a fragment 25 only of the phonograph cover being shown,

Fig. 2, a vertical section through the upper portion of the phonograph,

Figs. 3 and 4, views similar to Figs. 1 and 30 2, respectively, showing a slightly modified form of construction, and

Fig. 5, a top plan view of a slightly modified form of brake.

The mechanism embodying the invention 35 herein is designed for use in connection with a conventional phonograph, such as embodies the cabinet 10 and rotary record table or support 11 which is carried by a shaft 12, the record 13 being adapted to loosely rest 40 upon the table 11, as seen in the several views. Such form of phonograph also comprises a swingingly mounted tone arm 14, the front end portion 15 of which carries a stylus 16 being pivoted at 17 to swing vertically, as will be readily understood. The

usual brake lever 18 is shown, whereby operation of the phonograph is usually controlled, this brake, with the present construction, being, however, only employed to 45 permanently arrest the phonograph or when the phonograph is to be stopped for some considerable period. Otherwise, the stop 18 is moved to released or in-operative position.

At the top of the phonograph cabinet is provided the usual cover 19, hinged at 20 to permit of upward swinging thereof.

The mechanism forming the subject matter of this application comprises, as shown in Figs. 1 and 2, a brake 20 which is pivoted at 21 so as to permit of the shoe 22 thereof 60 engaging with the periphery of the record table, as will be readily understood. A helical tension spring 23 cooperates with said brake 20 to normally hold the same in released or inoperative position. Connected 65 with said brake 20 is an operating cord 24, which passes through a guide eye 25 and being then connected with the tone arm 14 of the phonograph. The arrangement is such, that when said tone arm is in initial 70 or starting position, the brake 20 will be held thereby in operative position or in engagement with the record table 11 to arrest movement of the latter.

The movable end 15 of said tone arm is 75 connected by means of a cord 26 with an eye 27 carried by the cover 19. The arrangement is such, that in the opening movement of said cover, said tone arm section 15 will be raised from engagement with the record, 80 as clearly seen in Fig. 2. Further, the arrangement is such, that, in the rendition of a record, when the stylus is positioned at the inner end of the tone groove of the record, the cord 26 will be positioned below the center 85 of oscillation of the tone arm 14, as seen in Fig. 1, or in such a position that, upon raising of the cover, not only will the tone arm section 15 be lifted from the record, but the tendency of the pull upon said cord 26 will 90 be such as to effect automatically the return swinging of tone arm 14 to its initial position. Hence, with this arrangement, it will be seen that upon rendition of a record, when the cover is raised to open position, 95 the tone arm will be automatically lifted from engagement with the record, swung back to initial position, and in the latter movement cause application of stop or brake 20 to effect automatic stopping of the phonograph. 100

In the form of construction shown in Figs. 3 and 4, a brake 20' is provided similar to the brake 20, but arranged for engagement with the inner side of the peripheral flange 105 of the record table or support. In this form, however, the brake operating cord 28 passes through guide eyes 29 and is connected with the eye 27 with which the cord 26 connected with the tone arm section 15 110 engages. With this arrangement, therefore, it will be seen that the opening move-

ment of the cover 19 performs directly the double function of lifting the tone arm member 15 from engagement with the record, and setting the brake 20'. In this form, 5 also, a cord 30 connects the tone arm 14 with the cord 28 so as to positively insure return swinging of the tone arm in the opening movement of the cover.

The cord 26 and eye 27 are so positioned, 10 relative to the pivotal axis of the tone arm 14, that when said tone arm is at its inner terminal movement, as illustrated in dotted lines in Figs. 1 and 3, the cord 26 will have passed beyond the said axis of said tone arm 15 so that any pull upon said cord will have a tendency to hold the tone arm in this position. This is of special advantage in that it permits of insertion or removal of a needle 15 without fear of the tone arm being swung 20 off to the side or toward initial position during the operation. Said cord and eye are, however, so positioned that when the needle has reached the inner terminal of the tone groove of the record, which is the intermediate 25 position of the tone arm shown in dotted lines in Figs. 1 and 3, said cord 26 will, as has before been pointed out, be positioned at the opposite side of the pivotal axis of the tone arm to insure automatic return 30 thereof to initial position upon lifting of the cover 19. The feature just described applies only to the construction seen in Fig. 1, inasmuch as in the construction shown in Fig. 3 the tone arm is connected directly with the 35 cover 19 so as to effect positive swinging of said tone arm to initial position upon lifting of the cover. In the construction seen in Fig. 1, the tone arm is not connected in this manner.

40 If desired, the brake employed may be of the construction seen in Fig. 5, in which the body thereof is formed of a wooden block 31 adapted to be pivotally secured at 32, said block carrying the shoe 33 secured thereto by 45 a staple 34.

While I have illustrated and described the preferred forms of construction for carrying my invention into effect, these are capable of variation and modification without departing 50 from the spirit of the invention. I, therefore, do not wish to be limited to the precise details of construction set forth, but desire to avail myself of such variations and modifications as come within the scope of 55 the appended claims.

Having described my invention, what I claim as new and desire to secure by Letters Patent is:—

1. The combination with a phonograph 60 having a rotary record support; a pivotally mounted tone arm; a movable cover, of means for automatically stopping operation of the phonograph upon rendition of a record, comprising an operative connection between 65 said tone arm and said cover whereby,

upon opening movement of said cover, said arm will be raised from engagement with the record; a brake coöperating with said record support; and means for applying said brake simultaneously with the movement of 70 said tone arm from engagement with the record, substantially as described.

2. The combination with a phonograph having a rotary record support; a pivotally mounted tone arm; a movable cover, of 75 means for automatically stopping operation of the phonograph upon rendition of a record, comprising an operative connection between said tone arm and said cover whereby, upon opening movement of said cover, said 80 arm will be raised from engagement with the record; a normally inoperatively positioned brake adapted for engagement with the record support; and means for applying said brake simultaneously with the movement of 85 said tone arm from engagement with the record, substantially as described.

3. The combination with a phonograph having a rotary record support; a pivotally mounted tone arm; a movable cover, of 90 means for automatically stopping operation of the phonograph upon rendition of a record, comprising an operative connection between said tone arm and said cover whereby, upon opening movement of said cover, said 95 arm will be raised from engagement with the record; a normally inoperatively positioned spring-held brake coöperating with said record support; and means for applying said brake simultaneously with the movement of 100 said tone arm from engagement with the record, substantially as described.

4. The combination with a phonograph having a rotary record support; a pivotally mounted tone arm; a movable cover, of 105 means for automatically stopping operation of the phonograph upon rendition of a record, comprising an operative connection between said tone arm and said cover whereby, upon opening movement of said cover, said 110 arm will be raised from engagement with the record; a brake coöperating with said record support; and an operative connection between said brake and tone arm whereby, upon return swinging of said tone arm, said 115 brake will be applied, substantially as described.

5. The combination with a phonograph having a rotary record support; a pivotally mounted tone arm; a movable cover, of 120 means for automatically stopping operation of the phonograph upon rendition of a record, comprising an operative connection between said tone arm and said cover whereby, upon opening movement of said cover, said 125 arm will be raised from engagement with the record; a brake coöperating with said record support; an operative connection between said brake and tone arm whereby, upon return swinging of said tone arm, said 130

brake will be applied; and an operative connection between said tone arm and said cover whereby, upon opening movement of said cover, said tone arm will be positively re-
5 turned to starting position, substantially as described.

In testimony whereof I have signed my

name to this specification in the presence of two subscribing witnesses.

RICHARD KUENSTLER.
